DESIGN FOR A DOLL

Pearl G. Lattos and Mamie Kern, Chicago, Ill.

Application October 26, 1944, Serial No. 115,979

Term of patent 14 years

(Cl. D34—4)

To all whom it may concern:

Be it known that we, Pearl G. Lattos and Mamie Kern, citizens of the United States of America, residing at Chicago, in the county of Cook and State of Illinois, have invented a new, original, and ornamental Design for Dolls, of which the following is a specification, reference being had to the accompanying drawing, forming part thereof.

The figure is a perspective view of a doll, showing our new design.

We claim:

The ornamental design for a doll, substantially as shown.

PEARL G. LATTOZ.
MAMIE KERN.
